**SWITCH CONSTRUCTION FOR HIGH VOLTAGE
A.C. POWER CIRCUITS HAVING ARCING HORNS
ARRANGED FOR CLOSING AGAINST HIGH
FAULT CURRENTS**

John J. Mikos, Highland Park, Ill., assignor to S & C Electric Company, Chicago, Ill., a corporation of Delaware
Filed July 15, 1963, Ser. No. 294,845
15 Claims. (Cl. 200—146)

This invention relates, generally, to circuit breakers and breakers, and it has particularly relation to the construction of switches for the use on high voltage alternating current power circuits operating at voltages of the order of 138 kv. It constitutes an improvement over the constructions shown in U.S. Patent No. 2,894,101, issued July 7, 1959, to S. I. Lindell et al. and No. 3,030,481, issued April 17, 1962, to W. A. Gussow et al.

Among the objects of this invention are: To provide a relatively stationary switch contact construction for engagement by a disconnecting switch blade that is capable of withstanding the stresses incident to closing the switch blade against fault currents of relatively great magnitude, for example fault currents of the order of 40,000 to 50,000 crest amperes; to arrange the contact construction in such a manner that it can be employed on circuits operating at 138 kv. or higher without requiring the use of special devices, such as corona balls, to avoid the effects of corona discharge; to employ for this purpose a pair of arcing horns arranged to maintain contact with the switch blade in a new and improved manner prior to its engagement with the relatively stationary switch contact and immediately after its disengagement therefrom; to construct each arcing horn of rod-like resilient material in an inverted U-shape or hair pin shape with one arm shorter than the other for engagement with one side of an arcing tip extending endwise from the switch blade, the arcing horns being located on opposite sides of the arcing tip and the distal ends of the shorter arms being freely movable with respect to each other; to attach the longer arms of the inverted U-shaped arcing horns to the base of the stationary switch contact to position the shorter arms in staggered relation on opposite sides of the contact tip when the switch blade is closed; to interconnect rigidly the longer arms of the inverted U-shaped arcing horns at a location well above their attachment to the base of the stationary switch contact and below the distal ends of the shorter arms; to employ a tie bar for making the rigid interconnection between the longer arms of the arcing horns; to position the inverted U-shaped arcing horns such that, when the switch blade is in the open position, the shorter arms extend to opposite sides of the path of the arcing tip in moving to the switch closed position; to limit the movement of the switch blade in the closing direction such that the arcing tip is not moved to a position below the distal ends of the shorter arms of the inverted U-shaped arcing horns; to locate the bight of the arcing horn nearer the axis of rotation of the switch blade above the arcuate path of the distal end of the arcing tip; and to arrange the coextensive portions of the arms of each arcing horn in generally parallel relation and in planes intersecting the arcing tip generally at right angles.

In the drawings:

FIG. 1 is a view, in side elevation, of a switch construction provided with a stationary switch contact embodying the present invention.

FIG. 2 is a view, at an enlarged scale, of the stationary contact construction, the view being taken looking from right to left in FIG. 1 with the switch blade out of contact engagement with the stationary switch contact.

FIG. 3 is a view, similar to FIG. 2, but showing the positions of the arcing horns when the arcing tip on the switch blade is located therebetween in the switch closed position.

5 FIG. 4 is a view, in side elevation, of the switch contact construction shown in FIGS. 2 and 3, certain parts being broken away in order to show the details of construction, and the distal end of the switch blade carrying the arcing tip being shown in the switch closed position.

10 FIG. 5 is a top plan view of the construction shown in FIG. 4, only the arcing tip being shown by broken lines and certain parts being broken away in order to show the details of construction.

15 FIG. 6 is a top plan view, at an enlarged scale, of the tie bar that is employed for rigidly interconnecting the longer arms of the arcing horns.

FIG. 7 is a side elevational view of the tie bar shown in FIG. 6, a portion being broken away in order to show the details of construction.

20 Referring now particularly to FIG. 1 of the drawings, it will be observed that the reference character 10 designates, generally, switch means in which the present invention is embodied. The switch means 10 includes a base, indicated generally at 11, that may be formed of a pair of rolled steel channels suitably secured together. Mounted on the base 11 are a first insulator 12, a second insulator 13, which is rotatable, and a third insulator 14. The second insulator 13 is rotatably mounted on a bearing 15 that is carried by the base 11 and it has an arm 16 extending therefrom for connection to a suitable operating linkage that is indicated, generally, at 17. It will be understood that, for three phase operation, three of the switch means 10 are mounted on a suitable switching structure in proper spaced relation, depending upon the voltage of the circuit, and suitable operating means connected to the operating linkage 17, is provided for effecting simultaneous rotation of the second insulator 13 of each switch means 10 for either opening or closing the circuit as may be required.

25 Extending upwardly from and rotatable with the second insulator 13 is a shaft 18. The shaft 18 extends through and is rotatably mounted on a mechanism housing 19 the details of construction of which are set forth in U.S. Patent No. 3,030,481 above referred to. The mechanism in the mechanism housing 19 is described in detail in the patent just referred to.

30 The shaft 18 extends through the mechanism housing 19 and carries at its upper end a switch crank 20 which is rotatable therewith. The switch crank 20 is pivotally connected to a link 21 that is pivoted at 22 to an arm 23 which extends from a switch blade 24 that forms a part of a disconnecting switch, indicated generally at 25. The switch blade 24 is pivoted at 26 on a bracket 27 which is carried by one wall of the mechanism housing 19. At its distal end the switch blade 24 is arranged to move into and out of high pressure contact engagement with a relatively stationary switch contact, shown generally at 28, which is carried by the first insulator 12. It will be understood that, on rotation of the second insulator 13 by the operating linkage 17, a corresponding rotation of the switch crank 20 is effected for swinging the switch blade 24 out of or into high pressure contact engagement with the relatively stationary switch contact 28, depending upon the direction of rotation. In this operation the switch blade 24 also is rotated about its longitudinal axis as described in U.S. Patent No. 2,818,474, issued December 31, 1957, to W. A. Gussow.

35 It is desirable that the switch blade 24 be opened only after the circuit has been opened previously by some other means. The reason for this is to prevent the drawing an arc between the distal end of the switch blade 24 and the relatively stationary switch contact 28 when the circuit is

interrupted under load which might result in damage to these parts or the creation of a fault by arcing over to an adjacent phase or to ground. For this purpose there is mounted between the mechanism housing 19 and a line terminal 29 which is carried by the third insulator 14, a current interrupter that is indicated, generally at 30. Preferably the current interrupter 30 is constructed as disclosed in U.S. application Serial No. 111,998, filed May 23, 1961, by John J. Mikos et al., now Patent No. 3,163-736, issued December 29, 1964. However, it will be understood that other circuit interrupters can be employed in lieu of the particular circuit interrupter 30 just referred to.

The relatively stationary switch contact 28 is mounted on a line terminal 32, which is carried by the first insulator 12. The present invention has particularly to do with improvement in the construction of the relatively stationary switch contact 28. More specifically it relates to the provision and arrangement of arcing horns, to be described, which facilitate the closing of the switch blade 24 against heavy current flow, such as the flow of fault current.

Except for the particular construction of the arcing horns, to be described, the details of construction of the relatively stationary switch contact 28 are generally as shown in U.S. Patent No. 2,894,101, issued July 7, 1959, to S. I. Lindell et al. FIGS. 2, 3, 4 and 5 show the details of construction of the relatively stationary switch contact 28. It includes a jaw contact frame base 33 that may be secured by bolts 34, FIG. 1, to the line terminal 32. Inverted U-shaped contact members 35-35 extend upwardly from opposite sides of the frame base 33 and include inner downwardly extending arms 36-36 for high pressure contact engagement with ears on the switch blade 24, one of which is shown by broken lines at 37 in FIG. 4. It will be understood that the switch blade 24 is rotated about its longitudinal axis to move the ears 37 into high pressure contact engagement with the inner faces of the downwardly extending inner arms 36-36. The contact members 35-35 also include outer arms 38-38 which are reinforced by back-up springs 39-39, the assembly being secured by bolts 40-40 to the opposite sides of the frame base 33. The distal ends of the inner arms 36-36 have a loading pin 43 extending therethrough. Leaf springs 44-44, extending along the outer sides of the inner arms 36-36, bear against the outer ends of the loading pin 43 and extend underneath pins 45-45 that project transversely through an equalizer bar 46 the ends of which project beyond the back-up springs 39-39 and through which loading pins 47-47 extend. As described in the Lindell et al. Patent No. 2,894,101, above referred to, this construction facilitates the movement of the switch blade 24 into and out of high pressure contact engagement with the switch contact 28.

With a view to cushioning the final movement of the switch blade 24 in the switch closing direction, a blade stop plunger 48 is employed as shown in FIG. 4. The blade stop plunger 48 is slideable in the upper end of a sleeve 49 that is formed integrally with the frame base 33. At the lower portion of the sleeve 49 bumper pads 50 are inserted for resiliently cushioning the stopping of the blade plunger 48 on impaction by the switch blade 24 when it is moved to the closed position. A pin 51, which extends transversely through the lower end of the blade stop plunger 48 and through an elongated slot 52 in each side of the sleeve 49, limits the movement of the blade stop plunger 48 to the extent permitted by the slots 52.

When the switch blade 24 is moved toward contact engagement with the switch contact 28 and the circuit is to be completed against the flow of fault current of relatively great magnitude, such as a flow of several thousands of amperes, particularly severe mechanical and electrical problems are encountered. It is conventional to employ horn gap constructions in switches for these applications.

When they are subjected to high fault currents, magnetic forces are created between the moving and stationary arcing terminals which tend mechanically to blow them apart. As a result arcing is prolonged or reestablished in open air. The open arc gives rise to considerable burning of the metallic conducting parts which produces much splatter of metal on the main contact areas as well as erosion of the arcing terminals.

In accordance with this invention arcing horns 55-55 are employed. They are of generally inverted U-shape or hair pin shape as is apparent from FIGS. 2 and 3. Preferably they are formed from resilient rod-like brass alloy conducting material having a circular cross section. For example, they may be formed of Everdur alloy. The arcing horns 55-55 include shorter arms 56-56 that are arranged to engage opposite sides of an arcing tip 57 that extends endwise from the switch blade 24 as shown more clearly in FIGS. 1 and 4 of the drawings. The arcing horns 55-55 are mounted on the frame base 33 in staggered relation so that, as shown in FIG. 5, the shorter arms 56-56 engage opposite sides of the arcing tip 57 in a spaced apart relation rather than opposite each other. The reason for this arrangement is to facilitate breaking loose the arcing tip 57 from the arcing horns 55-55 under icing conditions or to permit its application thereto under these conditions. The arcing horns 55-55 also include downwardly extending longer arms 58-58 which are generally parallel to the shorter arms 56-56 in the region where they are coextensive. It will be noted that the longer arms 58-58 and consequently the shorter arms 56-56 are inclined outwardly with the result that the distal ends 59-59 of the shorter arms 56-56 intersect on opposite sides of a plane that is indicated by a broken line 60, this being the plane of movement of the arcing tip 57 as it is rotated into or out of the switch closed position. Preferably the angle of inclination of the arcing horns 55-55 away from the plane 60 is of the order of 5°. The lower ends 61-61 of the longer arms 58-58 extend vertically upwardly from the frame base 33. They are positioned, as shown in FIG. 4, in staggered relation in a boss 62 that is formed integrally with the frame base 33, and they are held in place in suitable apertures therein by set screws 63.

It will be noted that the distal ends 59-59 of the shorter arms 56-56 are free of attachment and that they can move independently of each other. However, it is desirable that, once the arcing tip 57 engages one or the other of the shorter arms 56-56, contact engagement therewith be maintained during the continued movement of the switch blade 24 to the switch closed position. In order to make certain that this contact engagement is maintained, a tie bar 64 is employed for rigidly interconnecting the longer arms 58-58 of the arcing horns 55-55 at a position, shown in FIGS. 2 and 3, well above the attachment of the lower ends 61-61 to the frame base 33 and immediately below the distal ends 59-59 of the shorter arms 56-56. FIGS. 6 and 7 show the details of construction of the tie bar 64. Preferably it is formed of brass alloy rod, such as Everdur alloy rod, and it has inclined circular openings 65-65 near its ends for receiving the outwardly inclined longer arms 58-58 of the arcing horns 55-55. The ends of the tie bar 64 are provided with threaded openings 66-66 for receiving socket head set screws 67, one of which is shown in each of FIGS. 2, 3 and 4.

By providing the tie bar 64 rigidly interconnecting the longer arms 58-58 of the arcing horns 55-55, contact engagement with one or the other of the shorter arms 56-56 is made certain when the switch blade 24 moves the arcing tip 57 into engagement therewith during the closing movement. Yet the shorter arms 56-56 are free to flex independently of each other in order to accommodate a substantial degree of misalignment between the switch blade 24 and the switch contact 28.

While the blade stop plunger 48 limits the closing

movement of the switch blade 24 such that the arcing tip 57, under normal operating conditions, is not moved below its position as shown in FIG. 3, there is a remote possibility that the arcing tip 57 might become positioned between the longer and shorter arms 56 and 58 of one or the other of the arcing horns 55-55. In FIG. 1 the broken line 68 indicates the arcuate path of the distal end 69 of the arcing tip 57. The arcing horns 55-55 extend upwardly above the frame base 33 to such a position that the bights 70-70, and particularly the bight 70 of the arcing horn 55 nearer the pivot axis 26 of the switch blade 24 is above the arcuate path represented by the broken line 68 of the distal end 69 of the arcing tip 57. With this arrangement, even if the arcing tip 57 should be positioned between the shorter and longer arms 56 and 58 of one or the other arcing horns 55-55, it could not engage the bight 70 of either of them and prevent the swinging of the switch blade 24 to the switch open position. While this action is unlikely, it is possible upon closing under excessive fault current conditions. Referring to FIG. 5, it will be understood that the magnetic forces acting under these conditions will tend to move the outer arcing horn 55 past the distal end of the arcing tip 57 while the inner arcing horn 55 is held against movement by the outer end of the switch blade 24. Thus the arcing tip 57 might enter the space between the arms 56-58 of the outer arcing horn 55. However, because the bight 70 is located above the arcuate path 68, the opening of the switch blade 24 is not prevented by engagement therewith of the arcing tip 57.

When current flows through the hair pin shaped arcing horns 55-55, magnetic forces are produced which tend to move the shorter arms 56-56 toward each other, thereby gripping the moving arcing tip 57 and maintaining metal to metal contact as soon as possible after pre-strike in air and until the ears 37 are in full contact engagement with the contact surfaces of the inner arms 36-36 of the switch contact 28 when the switch blade 24 is swung to the completely closed position. During the closing sequence of operations, the tie bar 64 provides a positive member for providing a point of reaction for the magnetic forces acting to move the short arms 56-56 toward the arcing tip 57 and away from the longer arms 58-58. The tie bar 64 also provides mechanical coupling between the longer arms 58-58 so that mechanical tuning fork vibrations are not caused when the arcing tip 57 strikes the shorter arms 56-56 with strictly mechanical metal to metal contact. Without the tie bar 64, if the arcing tip 57 should strike one of the shorter arms 56, it would tend to move away from the other shorter arm 56 since bight 70 is close enough to the impact point to transmit the impact force to the associated longer arm 58 which would then move about its lower end support in the boss 62. There would then be a tendency for the struck shorter arm 56 to move out of contact with the arcing tip 57 and a sputtering arc to be drawn. When the longer arms 58-58 are connected by the tie bar 64, such movement of the impacted arcing horn 55 is restrained and the other arcing horn 55 is moved to maintain both shorter arms 56-56 in contact with the arcing tip 57 without creation of mechanical oscillations.

Damage incident to closing of the switch blade 24 against flow of high fault current is further minimized by moving it at high speed through the pre-strike arc distance. This is accomplished by connecting an operator to the linkage 17 that is capable of swinging the arcing tip 57 through the pre-strike zone in a relatively short time of the order of 0.1 second or less.

What is claimed as new is:

1. In a switch, in combination:

- (a) a relatively stationary switch contact,
- (b) a switch blade rotatably mounted at one end for swinging movement into contact engagement with said switch contact,

- 5
- (c) an arcing tip forming an extension of the distal end of said switch blade, and
  - (d) a pair of inverted U-shaped flexible arcing horns on opposite sides of and engaging said arcing tip in the closed position of said switch blade,
  - (e) the arms of said arcing horns being of unequal length with the longer arm of each pair attached to said switch contact and the shorter arm free to flex independently of the other shorter arm for engagement with opposite sides of said arcing tip,
  - (f) said arcing horns being positioned in generally parallel planes intersecting said arcing tip generally at right angles with the shorter arms engaging said arcing tip in staggered relation,
  - (g) said shorter arms in the switch open position extending to opposite sides of the path of said arcing tip in moving to the switch closed position.

2. The invention, as set forth in claim 1, wherein stop means limit the movement of the switch blade in the switch closing direction whereby the arcing tip is prevented from moving to a position below the distal ends of the shorter arms of the arcing horns.

20 3. In a switch, in combination:

- (a) a relatively stationary switch contact,
- (b) a switch blade rotatably mounted at one end for swinging movement into contact engagement with said switch contact,
- (c) an arcing tip forming an extension of the distal end of said switch blade, and
- (d) a pair of inverted U-shaped flexible arcing horns on opposite sides of and engaging said arcing tip in the closed position of said switch blade,
- (e) the arms of said arcing horns being of unequal length with the longer arm of each pair attached to said switch contact and the shorter arm free to flex independently of the other shorter arm for engagement with opposite sides of said arcing tip,
- (f) said arcing horns being positioned in generally parallel planes intersecting said arcing tip generally at right angles with said shorter arms engaging said arcing tip in staggered relation,
- (g) the coextensive portions of the arms of each arcing horn being generally parallel in unstressed condition and inclined outwardly at acute angles away from the path of said arcing tip in moving to switch closed position.

4. The invention, as set forth in claim 3, wherein the portions of the longer arms immediately above the attachment to the switch contact are generally parallel to each other and the portions thereabove diverge at acute angles away from the plane of the path of the arcing tip.

5. In a switch, in combination:

- (a) a relatively stationary switch contact,
- (b) a switch blade rotatably mounted at one end for swinging movement into contact engagement with said switch contact,
- (c) an arcing tip forming an extension of the distal end of said switch blade,
- (d) a pair of inverted U-shaped flexible arcing horns on opposite sides of and engaging said arcing tip in the closed position of said switch blade,
- (e) the arms of said arcing horns being of unequal length with the longer arm of each pair attached to said switch contact to provide flexibility for said arcing horns to accommodate limited misalignment of said arcing tip therewith and the shorter arm free to flex independently of the other shorter arm for engagement with opposite sides of said arcing tip for good contact engagement therewith, and
- (f) means spaced a substantial distance above the attachment of said longer arms to said switch contact and below the distal ends of said shorter arms, said means rigidly interconnecting said longer arms and providing a point of reaction for the magnetic forces

on said shorter arms due to current flow therein and in said longer arms.

6. The invention, as set forth in claim 5, wherein the inverted U-shaped arcing horns are positioned in generally parallel planes intersecting the arcing tip generally at right angles with the shorter arms engaging said arcing tip in staggered relation.

7. The invention, as set forth in claim 6, wherein, when the switch blade is in the open position, the shorter arms of the arcing horns extend to opposite sides of the path of the arcing tip in moving to the switch closed position.

8. The invention, as set forth in claim 7, wherein stop means limit the movement of the switch blade in the switch closing direction whereby the arching tip is prevented from moving to a position below the distal ends of the shorter arms of the arcing horns.

9. The invention, as set forth in claim 6, wherein the arcuate path of the distal end of the arcing tip is below the bight of the arcing horn nearer the axis of rotation of the switch blade.

10. The invention, as set forth in claim 6, wherein:

- (a) the coextensive portions of the arms of each arching horn are generally parallel, and
- (b) they are inclined outwardly at acute angles away from the path of the arcing tip in moving to the switch closed position.

11. The invention, as set forth in claim 10, wherein the portions of the longer arms immediately above the attachment to the switch contact are generally parallel to each other and the portions thereabove diverge at acute angles away from the plane of the path of the arcing tip.

12. In a switch, in combination:

- (a) a relatively stationary switch contact,
- (b) a switch blade rotatably mounted at one end for swinging movement into contact engagement with said switch contact,
- (c) an arcing tip forming an extension of the distal end of said switch blade,
- (d) a pair of inverted U-shaped flexible arcing horns on opposite sides of and engaging said arcing tip in the closed position of said switch blade,

5

10

15

20

25

30

40

(e) the arms of said arcing horns being of unequal length with the longer arms of each pair attached to said switch contact and the shorter arm free to flex independently of the other shorter arm for engagement with opposite sides of said arcing tip, and

(f) means spaced a substantial distance above the attachment of said longer arms to said switch contact and below the distal ends of said shorter arms, said means rigidly interconnecting said longer arms and comprising a tie bar extending transversely of said longer arms and secured at its ends thereto.

13. The invention, as set forth in claim 12, wherein:

- (a) the arcing horns are formed of rod-like resilient material having a circular cross section,
- (b) the tie bar has a transversely extending circular opening near each end for receiving therethrough the respective longer arm, and
- (c) means cooperate with said tie bar and the longer arms to hold the former in position on the latter.

14. The invention, as set forth in claim 12, wherein, when the switch blade is in the open position, the shorter arms of the arcing horns extend to opposite sides of the path of the arcing tip in moving to the switch closed position.

15. The invention, as set forth in claim 12, wherein:

- (a) the coextensive portions of the arms of each arching horn are generally parallel, and
- (b) they are inclined outwardly at acute angles away from the path of the arcing tip in moving to the switch closed position.
